To all whom it may concern:

Be it known that I, GAVIN ROWE, a subject of the Queen of Great Britain, residing at Bridgeport, in the county of Fairfield and State of Connecticut, have invented and produced a new and original Design for Pencils; and I do declare the following to be a full, clear, and exact description of the same, reference being had to the accompanying drawing, forming a part thereof, and which represents my design.

The leading feature of my design consists in a pencil-case having a round body, a head, a square portion next to said head, a screw-threaded end opposite the head, and a tapered tip.

1 denotes the plain round body portion of

the pencil-case; 2, the head; 3, the square portion next to the head; 4, the screw-threaded part or end opposite the head; 6, the tapered tip, and 5 the pencil-lead projecting from the hollow case at the pencil-tip.

I claim—

The design for a pencil-case, consisting of the hollow body having the plain round portion 1, head 2, square portion 3 next to the said head, threaded part 4, and tapered tip 6, substantially as shown and described.

In testimony whereof I affix my signature in presence of two witnesses.
